UNITED STATES PATENT OFFICE.

JOHN F. SKIRROW, OF EAST ORANGE, NEW JERSEY.

MULTIPLE CONTACT FOR ELECTRICAL CONDENSERS.

No. 832,632.

Specification of Letters Patent.

Patented Oct. 9, 1906.

Application filed March 14, 1905. Serial No. 250,125.

To all whom it may concern:

Be it known that I, JOHN F. SKIRROW, a citizen of the United States, residing at East Orange, county of Essex, and State of New Jersey, have invented certain new and useful Improvements in Multiple Contacts for Electrical Condensers, of which the following is a specification, reference being had therein to the accompanying drawings, in which—

- 10 Fig. 1 is a perspective view of a condenser complete; Fig. 2, a transverse sectional view of the condenser-case, showing the multiple contact in position therein; Fig. 15 3, a plan or edge view of the block of insulation on which the contacts are mounted; Fig. 4, a plan view of the apparatus, showing the condenser-plates in diagram; Fig. 5, a vertical sectional view on the line V V of Fig. 4; Fig. 6, a similar view on the line VI VI of Fig. 4; Fig. 7, a detail face of the dial and pointer used to indicate the position of the movable contact-bars, and Fig. 8 a diagrammatic view of the device adapted for use in a resistance-box.
- 20 25 One of the many objects of this invention is to provide a multiple contact by means of which when used in a condenser the line may be connected to the groups of inductive sheets or plates progressively one after the other in order that as many of said sheets in the condenser as may be desired may be charged. Of course it will be understood that the device may be applied to a resistance-box in such a manner that the resistance may be 30 35 cut out or cut in the circuit.

Another object of the invention is to provide rotating means for controlling and moving the contact-bars and to provide a dial and pointer in connection with said rotating means by means of which the exact position of the movable contacts may be indicated.

Referring to the various parts by numerals, 1 designates the condenser-case, and 2 the front piece or face-plate thereof. The condenser-case contains superposed sheets of conducting and dielectric material arranged in the usual manner in condensers and as indicated in diagram in Fig. 4. On the inner side of this front piece is secured a long block 3 of insulation. As shown in Fig. 2, this block extends entirely across the interior of the casting and is formed with a longitudinal boss or enlargement 4. In this enlargement midway its ends is formed a broad vertical-channel 5, and in the vertical face of it, on each side of the channel 5 are formed parallel vertical

narrow grooves 6. In each of these grooves is mounted a finger 7, one of whose ends curves inward toward the face-plate 2 to form a contact-point. These fingers are secured in position by means of screws 8. By reference to Fig. 2 it will be noted that the contact-fingers on the right-hand side of the channel 5 extend slightly above the enlarged central part 4 of the block 3 and are adapted to be engaged by an upper contact-bar, while on the other or left-hand side of the channel 5 the free ends of the fingers extend downward and are adapted to be engaged by a lower contact-bar, as hereinafter described. The lower ends of one set of these fingers and the upper ends of the other set of fingers are connected by wires 8 to one set of plates 9 of the condenser, as shown in Fig. 4, the other set of plates 9^a of the condenser being connected, through wire 10 and post 10^a, to the ground.

The ends of the contact-fingers, which are electrically connected to the inductive plates of the condenser, are inclined alternately upward and downward, as shown in Figs. 5 and 6, and between these bent ends are laid the insulating strips or cords 11, the ends of these strips or cords being connected to the supporting-block. Extending through the face-plate 2 and the body of the supporting-block 3 is a shaft 12, on the inner end of which in the channels 5 is mounted a gear-wheel 13, which meshes with racks 14, formed on the upper edges of the upper and lower bar-contacts 15. These bar-contacts rest and slide on the upper and lower surfaces, respectively, of the enlargement 4 of the supporting-block and are retained in position in mesh with the gear 13 by means of retaining-clips 16, secured to the supporting-block 3 and extending over and on the inner side of the rack-bars 15. The upper and lower edges of the upper and lower contact-bars, respectively, are grooved to receive the guide-bars 17, which are rigidly supported on the enlargement 4, as shown in Fig. 2. These guide-bars serve to retain the bar-contacts in position on the enlargement 4 and guide them in their movement. The free ends of the fingers 7 extend into the path of these contact-bars, so that when said bars are moved forward they contact with the ends of the fingers, as shown in Fig. 5, the engaging end of the bar being rounded slightly, as shown at 15^a in Fig. 4, in order that the said bar will not bind on the fingers.

As shown in Fig. 2, the upper contact-bar is slightly in advance of the lower bar—that is, it is nearer the first contact-finger of the series. The result of this is that when the gear 13 is rotated in the proper direction the upper contact-bar will engage the first finger 7 of the upward-extending series before the lower-bar has engaged the first finger of the downward-extending series. These bars are so arranged that the fingers will be engaged one at a time, alternating in the upper and lower series.

The contact-bars are electrically connected to the post 18 by means of wires 19, which connect said post to the shaft of the gear 13 and to the retaining-clips 16.

On the outer side of the face-plate 2 concentric with the shaft 12 is secured the dial-plate 20, which is provided with suitable graduations or indications to indicate the positions of the reciprocable contact-bars. On the outer end of the shaft 12 is rigidly secured a knob 21, which carries a pointer 22, which is adapted to be moved around the dial. It will be readily seen that by rotating the knob 21 the contact-bars will be simultaneously moved to progressively engage the contact points or singers. It will be noted that by this means the line may be connected to any number of induction-plates in the condenser from one group to the entire number of plates used.

In Fig. 8 the device is arranged for use in a resistance-box. In this figure only the ends of the fingers are shown, which are electrically connected to the resistance, it being unnecessary to show the device in greater detail. It will be readily understood that the reciprocable contacts may be moved to progressively engage the contact-points and to thereby very gradually cut out the resistance. It will of course be understood that when the contacts are returned to their normal positions the resistance will be gradually cut in the circuit.

It will of course be understood that the device will be put up in various forms and may be adapted for use in various electrical apparatus, and I therefore do not wish to be limited to the use of the device in connection with a condenser.

Having thus described my invention, what I claim as new, and desire to secure by Letters Patent, is—

1. A multiple-contact device comprising a block of insulating material formed with a series of parallel grooves or channels, contact-fingers arranged in said channels, a slidable contact-bar mounted on said block, and adapted to progressively engage the contact-fingers, a rotatable device for moving said bar, and means carried by said rotating device to indicate the position of the contact-bar.

2. A multiple-contact device comprising a

support, two series of contact-fingers carried by said support, a slidable contact-bar for each series of contact-fingers, a rotatable device for simultaneously operating said bars to cause them to progressively engage the contact-fingers, and means carried by the rotatable device to indicate the positions of the contact-bars.

3. A multiple-contact device comprising a block of insulating material formed with a series of narrow grooves or channels in its face, a series of contact-fingers arranged in said grooves, a slidable contact-bar arranged on said insulating-block, means for supporting and guiding said contact-bar, said bars being formed with gear-rack on their edge, a pinion in engagement with said rack, a rotatable device connected to said pinion, means to electrically connect the line-wire to the slidable contact.

4. A multiple-contact device comprising a block of insulating material with two series of parallel grooves or channels in its face, a series of contact-fingers in said grooves, one set of fingers projecting on one side of the block, and the other projecting on the other side, a slidable contact-bar for each series of contact-fingers, means for supporting and guiding said bars on the insulating-block, a pinion mounted on said block and between the series of contact-fingers, said pinion being arranged to engage both of the contact-blocks, means connected to said pinion and adapted to rotate it, means to electrically connect the line-wire to both contact-bars.

5. A condenser comprising superposed sheets of conducting material, a suitable casing therefor, a block of insulating material secured within said casing, and formed with two series of parallel grooves or channels, contact-fingers arranged in said channels, one end of each of said contact-fingers being independently electrically connected to a series of said conducting-sheets, a long slidable contact-bar for each set of contact-fingers, said bar being adapted to engage all of said set of said fingers, means for supporting and guiding said bars, each of said bars being formed with a gear-rack on one edge, a pinion located between the two series of contact-fingers and adapted to engage the racks on the contact-bars, means to electrically connect the line-wire to both of said contact-bars, means outside of the casing adapted to rotate the pinion and means to indicate the positions of the contact-bars.

6. A multiple contact comprising two series of contact-points arranged on opposite sides of a center, a reciprocable long bar-contact for each series of contacts, a gear-rack formed on said bar, a gear engaging both of said racks, whereby when the gear is rotated the bars will be moved in opposite directions and caused to engage one or more of the contact-points.

7. A multiple contact comprising two series of contact-points, a reciprocable contact-bar for each line of points, one of said bars being slightly in advance of the other, and a rotating device adapted to move both bars, whereby any number of the points may be connected to the bars.
8. A multiple-contact device comprising a block, a series of contact-fingers arranged thereon, insulating material being arranged between and separating said fingers, a slideable contact-bar mounted on said block and adapted to progressively engage the contact-fingers, a rotatable device for moving said bar, and means carried by said rotating device to indicate the position of the contact-bar.
9. A multiple-contact device comprising a support, a series of contact-fingers arranged on said support, a contact device adapted to be brought progressively into contact with an increasing number of said contact-fingers, a rotatable device for moving said contact-
- bar, and means carried by said rotatable device to indicate the position of said bar.
10. A condenser comprising a pile comprising two sets of sheets of conducting material, a casing therefor, a series of contact-points within the casing, said points being connected to one set of sheets, a movable contact-bar within the casing, a rotatable device adapted to move the contact-bar, means whereby said rotatable device will indicate the position of the contact-bar and two binding-posts on the outer side of said casing, one of said posts being electrically connected to the contact-bar, and the other being electrically connected to the other set of sheets.

In testimony whereof I hereunto affix my signature, in the presence of two witnesses, this 8th day of March, 1905.

JOHN F. SKIRROW.
